Primary Examiner — Mojtaba Tehrani

CLAIM

The ornamental design for a humidifier cooling and heating fan as shown and described.

DESCRIPTION

FIG. 1 is a front perspective view of a humidifier cooling and heating fan showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is an enlarged detail view taken from portion 9 of FIG. 1;

FIG. 10 is an enlarged detail view taken from portion 10 of FIG. 2; and,

FIG. 11 is an enlarged detail view taken from portion 11 of FIG. 3.

The evenly broken lines depict unclaimed portions of the humidifier cooling and heating fan; the dash-dot broken lines disclose unclaimed bounds of the isolated and enlarged views; the broken lines form no part of the claimed design.

1 Claim, 11 Drawing Sheets
